(57) CLAIM

The ornamental design for a musical instrument including a reel-like structure, as shown and described.

DESCRIPTION

FIG. 1 is a top perspective view of a musical instrument including a reel-like structure showing my new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken line portion of the figure drawings is included to show subject matter that forms no part of the claimed design.
